[57] CLAIM

The ornamental design for a solid particle collecting container for a dental equipment stand, as shown and described.

DESCRIPTION

FIG. 1 is a front elevational view of a solid particle collecting container for a dental equipment stand showing my new design;

FIG. 2 is a top plan view;

FIG. 3 is a side perspective view;

FIG. 4 is a side elevational view;

FIG. 5 is a bottom plan view; and
FIG. 6 is a sectional view thereof taken on the line 6—6
of FIG. 2.

FIG. 1.

FIG. 2.
